(57) **CLAIM**

The ornamental design for a "chair," as shown and described.

DESCRIPTION

FIG. 1 is an isometric view of one embodiment of my chair;
FIG. 2 is a front view of the chair;
FIG. 3 is a rear view of the chair;
FIG. 4 is a left side view of the chair;
FIG. 5 is a right side view of the chair;
FIG. 6 is a top view of the chair;
FIG. 7 is a bottom view of the chair;
FIG. 8 is an isometric view of an alternative embodiment of
the chair;
FIG. 9 is a front view of the embodiment of FIG. 8;
FIG. 10 is a rear view of the embodiment of FIG. 8;
FIG. 11 is a left side view of the embodiment of FIG. 8;
FIG. 12 is a right side view of the embodiment of FIG. 8;
FIG. 13 is a top view of the embodiment to FIG. 8; and,
FIG. 14 is a bottom view of the embodiment of FIG. 8.
The broken lines depict environmental subject matter only
and form no part of the claimed design.
